(57) **CLAIM**

The ornamental design for a hook, as shown and described.

DESCRIPTION

FIG. 1 is a perspective view of a hook showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a partially enlarged perspective view thereof, illustrating a slot portion of the hook in FIG. 1.

The broken lines in FIGS. 1 and 8 are for the purpose of illustrating the boundary of corresponding views, and form no part of the claim.

1 Claim, 8 Drawing Sheets

FIG.1

FIG.2

FIG.3
